UNITED STATES PATENT OFFICE.

CHARLES H. JOY, OF CHICAGO, ILLINOIS, ASSIGNOR OF ONE-HALF TO
WILLIAM J. DRIVER, OF CHICAGO, ILLINOIS.

BURGLAR-ALARM.

No. 834,736.

Specification of Letters Patent.

Patented Oct. 30, 1906.

Application filed October 7, 1905. Serial No. 281,735.

To all whom it may concern:

Be it known that I, CHARLES H. JOY, a citizen of the United States, residing at Chicago, in the county of Cook and State of Illinois, have invented certain new and useful Improvements in Burglar-Alarms, of which the following is a specification.

This invention relates to improvements in an alarm-giving device which is adapted to be attached to a door or the sash of a window in such a manner as to sound an alarm in the movement of either in the operation of opening the same; and it consists in certain peculiarities of the construction, novel arrangements, and operation of the various parts thereof, as will be hereinafter more fully set forth and specifically claimed.

The principal object of the invention is to provide an alarm of the above-named character which shall be simple and inexpensive in construction, strong, durable, and effective in operation, and so made that it may be readily secured to the door or window-sash without the use of screws or nails when so desired.

Another object is to provide a burglar-alarm which may be adjusted when the door or window is in its open position and will automatically set itself upon the closing of the door or window, so as to sound an alarm when the same is opened.

A further object is to so construct the parts of the device that they may be arranged in such a manner that the door or window may be opened without giving an alarm.

Other objects and advantages of the invention will be disclosed in the subjoined description and explanation.

In order to enable others skilled in the art to which my invention pertains to make and use the same, I will now proceed to describe it, referring to the accompanying drawings, in which—

Figure 1 is a view in elevation of a portion of a door and a part of its jamb, showing the alarm secured to the former and the parts in position ready to sound an alarm upon the opening of the door. Fig. 2 is a front view of the alarm, showing it detached. Fig. 3 is a bottom plan view thereof, showing the base of the casing broken away to illustrate the arrangement of the springs employed for giving the alarm. Fig. 4 is a similar view with the bottom of the casing and the spring

for actuating the alarm mechanism removed, 55 but showing the controlling-bar and the spring for actuating the same. Fig. 5 is a plan view of the casing with the bell removed therefrom and showing the alarm mechanism mounted thereon. Fig. 6 is a detached 60 perspective view of the retaining and releasing clip for the controlling-bar. Fig. 7 is a rear view in elevation thereof, showing by dotted lines the position to which the sliding plate thereon may be moved. Fig. 8 is a detail view of the striking-hammer and a portion of its arm. Fig. 9 is a view in side elevation of a portion of a window-casing and a part of its sash, showing the alarm mounted on the latter with its parts arranged ready 70 to give an alarm when the sash is raised. Fig. 10 is a fragmental view of the window-frame and the controlling-bar, showing the engaging device for said frame mounted on the bar. Fig. 11 is a detached perspective 75 view of the engaging device. Fig. 12 is a plan view of the casing with the bell and alarm mechanism removed, but showing the controlling-bar and striking-hammer in position thereon. Fig. 13 is a plan view of the 80 base or bottom plate of the casing; and Fig. 14 is an enlarged side view thereof, partly in section and partly in elevation, showing the means for securing the alarm to the door or window-sash.

Like numerals of reference refer to corresponding parts throughout the different views of the drawings.

The reference-numeral 20 designates a portion of a door and 21 a part of the door-frame. The alarm is secured to the door near its free edge, and the frame has secured thereon the retaining and releasing clip for the controlling-bar of the alarm, which consists of a circular casing 22, having its top closed, but provided in its walls with diametrically-disposed slots 23 and 24 for the reception and operation of the controlling-bar 25, which extends across the casing and has its ends projecting through said slots, as is clearly shown in Figs. 100 3 and 4 of the drawings. The lower edge of the casing 22 is provided with diametrically-disposed projections 26, which provide a convenient means for securing the base or bottom 27 to the casing, which base is circular in 105 form and is provided with recesses 28, located diametrically opposite each other for the reception of the projections 26, which may be

turned under the bottom of the base, thus firmly securing it to the casing. As is clearly shown in Figs. 2, 12, 13, and 14, the base 27 is provided with outwardly-projecting lugs 29 and 30, which are arranged diametrically opposite each other and at right angles with respect to the recesses 28 in the base. The lug 29 is provided on its lower surface with a downwardly and inwardly projecting tooth 31, and the lug 30 is formed with an opening 32, in which is fulcrumed a lever 33, which is provided on its inner portion with one or more downwardly and inwardly projecting teeth 34, which teeth, as well as the tooth 31, is for the purpose of engaging the door or window-sash so as to hold the alarm in position thereon, and it is evident that by raising the lever 33 to the position indicated by dotted lines in Fig. 14 and by pressing the base 20 against the surface of the door or window-sash the tooth 31 will be caused to pierce the wood, when by turning the lever down to the position shown by continuous lines in said figure the teeth 34 thereon will be forced into the wood, and thus firmly hold the alarm in position. Extending loosely and vertically through the top 35 of the casing is a revoluble spindle 36, which also passes through a vertical sleeve 37, mounted on the upper surface 30 of a plate 38, which is used to hold the escape- 35 ment-wheel 39 and a train of gears 40 in place on the top 35 and in connection with the spindle, the upper portion of which is screw-threaded and passes through a central opening 40 in the bell 41 and has secured on its upper end nuts 42 and 43, used for holding the bell in place. That portion of the spindle 36 within the casing is provided with a projection 44, to which one end of the mainspring 45 is connected, the other end of which is secured to a projection 46 on the inner surface of the casing, as is clearly shown in Fig. 3 of the drawings. Pivotal secured on the top of the casing near one of its ends is an arm 47, 45 which carries on one of its ends a hammer 48, which is loosely mounted on the arm 47 and is adapted to strike the inner surface of the bell. On the other end of the arm 47 is an anchor-pawl 49, which engages the escape- 50 ment-wheel 39 and controls the movement thereof. As shown in Fig. 4, the controlling-bar is provided with a longitudinal slot 50 to receive the spindle 36 and has on its upper surface a pin 51, which operates in a slot 52 in the top of the casing, so as to impinge the inner surface of the striking-arm 47 and to hold it against the bell, so as to prevent vibration of the arm. One end of the bar 25 has fulcrumed thereon a cam-lever 53 to coact 55 with the casing 22, so as to hold the said bar in its retracted position, as shown by dotted lines in Fig. 3, and thus lock the bar against longitudinal movement. The bar 25 is provided near its other end with a recess 54 for the purpose of engaging the casing at one

end of the slot 23, so as to set said bar and the alarm mechanism.

The retaining and releasing clip for the controlling-bar 25 consists of an apertured plate 55 to be secured to the door, which plate has an outwardly-extending portion 56, the upper end of which is provided with a transverse slot 57 for the reception of the front end of the bar 25 under certain conditions. One of the side edges of the portion 75 56 is provided with a flange 58, which extends inwardly toward the alarm and has a lateral extension 59, which is downwardly inclined at its upper part. The portion 56 has at about its middle a transverse slot 60 for the 80 operation of a pin 61 on a sliding plate 62, located on that surface of the portion 56 adjacent to the part 59. The upper portion of the plate 62 is provided with a recess 63, so that when it is slid to the position indicated 85 by dotted lines in Fig. 7 the front end of the bar 25 may project through the slot 57 on a slight movement of the door, thus providing a safety or additional lock for the door.

When the device is intended to be used on a window-sash, the same construction as above described is employed, except that the retaining and releasing clip is omitted, and the front end of the bar 25 has fitted thereon an engaging device for the window-frame 64, 90 which consists of a socketed member 65, having on one of its sides a toothed dog 66, which is pivotally secured to the member 65, as is clearly shown in Fig. 11 of the drawings. The member 65 has on its side opposite the dog 66 a projection 67 to fit in the recess 54 of the bar 25, so as to prevent that edge of said bar catching or engaging the casing, thereby permitting of the free longitudinal movement of the bar. 105

From the foregoing and by reference to the drawings it will be seen and clearly understood that by turning the nut 43 on the upper end of the stem 36, the mainspring 45 will be tightened or wound on said stem, and it may be held in its coiled or tightened position by means of the lever 53 or by means of the shoulder 54 engaging the casing, which latter engagement will be caused when the door is closed by the inclined part of the 110 flange 59 on the retaining-clip, for it is apparent that when the bar 25 is retracted and held in the position shown by dotted lines in Fig. 3 by means of the lever 53 and the door is closed the beveled portion of the flange 59 115 will force the bar 25 to one side, so that the recess 54 will engage the casing. In this arrangement of the parts it is apparent that the door may be opened and closed without giving an alarm; but if it is desired that an alarm shall be given the lever 53 should be released and the bar 25 disengaged from the casing at its front end, so that as soon as the said end of the bar is out of engagement with the retaining and releasing clip the bar will be pro- 120 125 130

jected, as shown by continuous lines in Fig. 3, which operation, through the medium of the spring 68 and pin 51, will release the striking-arm 47, thus permitting it to vibrate against the bell. By sliding the plate 62 outwardly, as shown by dotted lines in Fig. 7, it is apparent that as the door is opened the bar 25 may be projected through the slot 57, thus permitting the alarm to be given and at the same time providing a safety-lock for the door. In using the device on a window-sash the same operation is performed, except that the toothed dog 66 will engage the window-frame instead of the retaining-clip as before. It will be understood that the spring 68 is connected at one of its ends to the bar 25 near its rear end and usually by means of the pin 51, and at its other end to that side of the bar opposite the recess therein, and that said spring serves not only to project the bar, but also to actuate it sideways, so that the recess 54 will engage the casing when the bar is retracted.

Having thus fully described my invention, what I claim as new, and desire to secure by Letters Patent, is—

In a burglar-alarm, the combination with a casing having a central opening and provided with diametrically opposite slots in its walls, of a base secured to the bottom of the casing and having outwardly-extending lugs,

one of said lugs having on its lower surface an inwardly and downwardly projecting tooth and the other lug having a recess, a lever fulcrumed on the recessed lug and having on its inner end a downwardly and inwardly projecting tooth, a spring-actuated controlling-bar located in the slots of the casing and projecting at its ends through the same, said bar having a longitudinal and a slight transverse movement and provided near its front end with a shouldered recess to engage the casing, a cam-lever fulcrumed on the other end of the bar, a revoluble spindle or stem mounted in the central opening of the casing, a bell supported at the upper portion of the spindle, a mainspring located in the casing and secured at one of its ends to the spindle and at its other end to the wall of the casing, alarm mechanism mounted on the top of the casing within the bell and connected to said spindle, a striking-arm pivoted on the top of the casing and having at one of its ends an anchor-pawl to engage a portion of the alarm mechanism, and a hammer loosely mounted on the other end of said arm, substantially as described.

CHARLES H. JOY.
